UNITED STATES PATENT OFFICE.

FULVIO DE FAZI, OF CLEVELAND, OHIO, ASSIGNOR OF ONE-HALF TO LOUIS DE PAOLA,
OF CLEVELAND, OHIO.

SANITARY NOODLE HAND PRESS.

Application filed August 12, 1926. Serial No. 128,816.

The objects of the invention are to provide improved forms of construction for a sanitary hand noodle press having the particular advantages of simplicity in construction, and increased efficiency and practicability in use, and which can readily be cleansed from all impurities.

The novel features of the device include, a base or support for the rolling and cutting mechanism, which is constructed in one unitary part, thus materially simplifying the construction.

This base member is provided with integral sides having vertical slotted openings, the edges of which act as guides and bearing surfaces, to secure the journals of the smoothing roller and of the cutting roller in place, thus permitting these rollers to be easily lifted out of their bearings to be cleansed or repaired.

It includes vertically slotted side plates, the slots in which form guide bearings for the roller journals, the said slots being provided each with a vertical guide edge 25 against which edges the said journals bear, and from which they cannot depart, thus insuring perfect parallelism of the roller journals and preventing the knives on the upper roller from wearing irregularly against the lower roller.

It includes also adjustable hinged arms or clamping means, so constructed and arranged as to exert both a downward and forward pressure upon the journals of the upper roller to which the knives are attached, in order to retain them in contact with the said vertical edges of the guide slots in the frame, and thus to preserve the parallel relation of the roller axes.

It includes a forked clamping frame constructed in one piece with the side arms, the edges of which are inclined to engage with the journals of the upper roller and force them forward against said vertical edges of said slots.

The invention further comprises the combination and arrangement of parts, herein-after described, illustrated in the accompanying drawings and specifically pointed out in the claims.

In the accompanying drawings, Fig. 1 is an end elevation of the device.

Fig. 2 is a plan thereof, and
Fig. 3 is a front elevation, and

Fig. 4 is a transverse section on the center line.

Fig. 5 is a view corresponding to Fig. 4 with the rolls removed, and

Fig. 6 is a perspective view of the frame. In these views A, A, are the vertical sides 60 of a metal frame, and B is the integral base member thereof.

C and D are feed rollers, the roller C being cylindrical and serving as a base upon which, the disc cutters E, E, accurately 65 spaced in the longitudinal surface of the roller D, bear when cutting the dough, which is flattened previously by passing it between suitable rollers.

In this manner the dough is separated into narrow strips forming commercial "noodles".

The rollers are provided with projecting journals F and G respectively, which revolve in the vertical V shaped slots H, H, 75 in the ends of the frame A.

One edge of each slot is vertical and the journals of the upper rollers are maintained in contact with this vertical edge, to preserve the accurate alignment of the ends of 80 the roller, and to insure that the longitudinal axes of the rollers are maintained exactly parallel with each other, so that there will be no variation in the character of the product, and the disc cutters will remain 85 sharp by reason of their vertical position. This is accomplished by means of the arms I, I, pivoted at J, J, in the frame, and connected by the cross bar K.

These arms are provided with the bearing edges L, L, which are curved downwardly and extended diagonally at M, M, thus serving to force the journals downwardly, to engage the knives against the roller beneath, and forwardly, to engage the 95 journals with the vertical guide edges of the slots aforesaid, thus preventing the rollers from getting out of their vertical alignment with each other.

The pivoted arms are adjustably secured 100 in position by means of a clamping screw N passing into the horizontal bar N' that rigidly connects the sides of the frame, and a nut N². This nut engages with the slotted lug N³ on the cross bar K.

The rear edges of the slots H, H are preferably inclined to facilitate the mounting of the roller journals therein.

Guard plates O and P are employed to prevent the adhesion of dough to the rollers. These plates are commonly employed and hence do not require a further description.

5 Gearing Q, Q, connect the rollers, and a handle R upon the lower roller is employed to operate the same.

The base frame may be attached in any convenient manner to a table for operating 10 the rollers.

Having described the invention what I claim as new, and desire to secure by Letters Patent is;

1. In a device of the character described, 15 a frame composed of integral base and side members, said side members having a vertical V shaped slot therein, the front edges of said slots being vertical, a lower cylindrical roller and an upper roller provided with 20 longitudinally spaced disc shaped knives thereon, journals for said rollers mounted in said vertical slots, and means on said frame for pressing the journals of the upper roller downwardly and laterally against said 25 vertical sides of said slots.

2. In a device of the character described, 30 a frame provided with a flat base and vertical sides, said sides having registering vertical V shaped slots therein, and said slots having vertical rear edges, upper and lower 35 rollers journalled in said slots, and means for pressing the journals of said upper roller downward and laterally against the vertical sides of said slots.

3. In a device of the character described, 40 a frame provided with a flat base and vertical sides, said sides having registering vertical V shaped slots therein, and said slots having vertical front edges and inclined rear

edges, upper and lower rollers journalled in 45 said slots, and adjustable means for pressing the journals of said upper rollers downwardly and laterally against the vertical sides of said slots.

4. In a device of the character described, 50 the combination with a frame having spaced vertical sides, said sides being provided with vertical bearing slots, each of said slots having a vertical front guide edge, of upper and lower rollers, said upper roller being provided with cutting knives, journals for said rollers mounted in said bearing slots, and arms pivoted in said frame and connected together across said frame, said arms being provided with downwardly extended bearing surfaces adapted to force said upper journals into engagement with said vertical guide edges, and to force said knives against said lower roller.

5. In a device of the character described, 55 the combination with a frame having spaced vertical sides, said sides being provided with vertical bearing slots, each of said slots having a vertical front guide edge, of upper and lower rollers, said upper roller being provided with cutting knives, journals for said frame mounted in said bearing slots and arms pivoted in said frame connected together across said frame, said arms being provided with downwardly extended bearing surfaces adapted to force said upper journals into engagement with said vertical guide edges, and to force said knives against 60 said lower roller, and means for adjusting the pressure upon said arms.

In testimony whereof I hereunto affix my signature.

FULVIO DE FAZI.
